A. Singer,
ATTORNEY.

UNITED STATES PATENT OFFICE.

LUIS ARNAVAT OLIVÉ, OF HABANA, CUBA.

OBTURATING DEVICE FOR NON-REFILLABLE FLASKS OR THE LIKE.

1,303,382.

Specification of Letters Patent. Patented May 13, 1919.

Application filed March 15, 1918. Serial No. 222,671.

To all whom it may concern:

Be it known that I, LUIS ARNAVAT OLIVÉ, a citizen of the United States of America, and a resident of Habana, Republic of Cuba, 5 have invented certain new and useful Improvements in Obturating Devices for Non-Refillable Flasks or the like, of which the following is a specification.

This invention relates to the receptacles 10 of a non-refilling nature or that can not be refilled once its contents have been removed and its object is to provide an obturating device which is applied in the lower part of the neck of flasks, jars, glasses and 15 generally to any receptacles of any shape that are used for containing products in a fragmentary, granular or powdered condition, this obturating device being so disposed that it easily permits the discharge 20 of the contained products but that at the same time may prevent the introduction of new solid matter in the receptacles thereby protecting same against the falsification that would result from the fraudulent re- 25 filling of the receptacles done after the original products contained therein have been discharged, whereby this invention results in a very advantageous application in the sale of such pharmaceutical products of a frag- 30 mentary, granular and powdered character.

The invention is described with reference to the figures of the annexed drawings, in which:

Figure 1 is a vertical section of an obturating device made of different pieces, applied in the neck of a flask.

Fig. 2 is a vertical section of the same obturating device made of an integral piece.

Fig. 3 is an upper plan view of the upper 40 piece of said obturating device.

Fig. 4 is a vertical section on line 4—4 of Fig. 3.

Fig. 5 is an upper plan view of the intermediate piece of said obturating device.

Fig. 6 is a vertical section on line 6—6 of Fig. 5.

Fig. 7 is an upper plan view of the lower piece of said obturating device.

Fig. 8 is a vertical section on line 8—8 of Fig. 7.

Fig. 9 is a vertical section of a modified form of obturating device applied to the neck of a flask.

Fig. 10 is an outer elevation of same obturating device.

And Fig. 11 is a vertical section on line 11—11 of Fig. 10.

This obturating device consists of a closed chamber which may be made of various pieces as shown in Figs. 1 and 9, or it can 60 also be made of a single piece as shown in Fig. 2, and this chamber presents a small opening 1 in its upper base and a small opening 2 in its lower base, the small openings corresponding with each other in vertical alinement as shown in Figs. 1 and 2, or they may not correspond with each other in vertical alinement as shown in Fig. 9, said openings 1 and 2 communicating with each other by means of a plurality of inclined surface conduits terminating at said openings, the lower opening 2 being closed by means of an inclined door 3 which by virtue of the gravity force, tends to maintain closed said lower aperture.

In Fig. 1 of drawings, the chamber constituting the obturating device is formed by three pieces, an upper piece 4, an intermediate piece 5 and a lower piece 6 all of which are of different height or depth and they 80 may have in horizontal section a circular shape as shown in the drawings, or polygonal such as square, rectangular, etc., always in conformity to the shape of the horizontal section of the neck 7 of the flask 85 within which said obturating member is adjusted by means of a small sleeve 8 of cork or any other suitable material, whose upper edge is covered on the outside by a rim or flange 9 laterally projecting from the upper piece 4. This upper piece has a vertical conduit 10 leading downwardly from opening 1, and one of whose sides forms an inclined surface 10' terminating in a wide opening 1' in the lower part of said upper piece 4. The intermediate piece 5 presents a vertical opening 5' disposed diametrically opposite the opening 1 of the upper piece 4 and laterally to said opening 5' there is formed a recess 11 limited by an inclined plane 11' that leads from the end of the lower opening 1' of the upper piece 4 diametrically opposite to opening 5' and terminating in this one. The lower piece 6 presents an opening or vertical conduit 2 located diametrically opposite the opening 5' of the intermediate piece 5 and which is closed on the top by means of an inclined door 3 mounted on a hinge 12 at its uppermost part, and from said vertical opening 110

2 and leading to opening 5' there is a vertical conduit 13, one of whose sides forms an inclined surface 13' terminating near the lowermost part of said inclined door 3, there being formed in the lower base of the lower piece 6 a slight recess 14 for directing the material from the interior of the flask toward the opening 2. For adjusting together in position the pieces 4, 5 and 6, each piece 5 or 6 is provided on its upper face with diametrically opposed shoulders that fit in grooves 16 provided in the lower face of pieces 4 and 5 respectively. Once the obturating device is adjusted with the sleeve 10 piece 8 a common cork plug 21 is placed upon the same.

In Fig. 9 of the drawings a modified form of the obturating device has been shown in which said device consists of two pieces 4 and 6 which are equivalent to the upper and lower pieces of the form shown in Figs. 1 and 2 of the drawings, the intermediate piece 5 having been omitted. The upper piece 4 is similar to the upper piece previously described. The lower piece 6 is provided with an opening or vertical conduit 2 which is diametrically opposite to opening 1 of the upper piece and it is closed by means of an inclined door 3 mounted on a hinge 12 at its uppermost part, and from which there is an upwardly directed vertical conduit 13, one of whose sides forms an inclined surface 13' leading from the lowermost part of said door 3 to the opposite end of the lower opening 1' of said upper piece 4. In this case there are provided lateral nerves 18 in the lower part of conduit 10 of the upper piece 4, intended to constitute engaging surfaces for the door 3 in its upward swinging movement.

In Figs. 10 and 11 there is shown a modified form of engagement between two successive pieces, and which consists of two vertical lugs 19 diametrically opposed provided in the upper face of the lower piece and 45 which fit in corresponding cuts 20 formed on the peripheral surface of the upper piece.

Once the flask is filled with the product

that is to contain, the described device is placed in the lower part of the neck and thereupon the product in question might be 50 discharged from the flask but it would not be possible to refill it again. In effect, in the form shown in Figs. 1 and 2 when the flask is inclined to pour out a certain amount of the product, the door 3 is automatically 55 raised and the product passes through opening 2, then slides upon the inclined surface 13' toward the intermediate opening 5' wherefrom it slides again upon inclined surface 10' until reaching opening 1 wherefrom 60 it comes out. However, if it is intended to fill up the flask again, the product would pass through conduit 10 and opening 5' and would slide upon the inclined surface 13' until falling on the door 3 that would be 65 caused to close by reason of the weight of the product itself gravitating upon said door, without being able to enter the interior of the flask.

In the form shown in Fig. 9 if it is intended to refill the flask the product would fall directly on the inclined surface 13' gravitating upon door 3 thus preventing same to swing outwardly, whereby the introduction of the product is thus prevented.

What I claim is:

A non-refillable receptacle including a neck, a plug, provided with a passage, in said neck, an abutment extending from the side wall of said passage into the same, the passage making an acute bend around said abutment, a flap valve hinged below said abutment, and a second abutment having its outer edge below the plane in which said flap valve is hinged, such second abutment extending 85 into the passage from the opposite side thereof and being adapted to have its outer edge engaged by the outer edge of the valve.

In testimony whereof I affix my signature in presence of two witnesses.

LUIS ARNAVAT OLIVE.

Witnesses:

N. JUBERT,
RAYMONDA DOMINGO.
